UNITED STATES PATENT OFFICE.

LEONARD E. BUMPASS, OF DALLAS, TEXAS.

LOCK-PROTECTING DEVICE.

1,413,573.

Specification of Letters Patent. Patented Apr. 25, 1922.

Original application filed August 16, 1920, Serial No. 403,739. Divided and this application filed January 13, 1921. Serial No. 436,879.

To all whom it may concern:

Be it known that I, LEONARD E. BUMPASS, a citizen of the United States of America, residing at Dallas, in the county of Dallas and State of Texas, have invented certain new and useful Improvements in Lock-Protecting Devices, of which the following is a specification, reference being had therein to the accompanying drawings.

10 This application is a division of my co-pending application Serial Number 403,739, filed August 16, 1920, for a "Means for protecting vaults, safes and the doors thereof." The aforesaid application has been devoted 15 to those features having to do with the protection of vault walls and the present application relates to means for protecting the lock of safes, vaults and the like. Experience has shown that burglars frequently succeed 20 in robbing safes, vaults and the like by knocking off the dials of the combinations lock and then punching the locks mechanism straight through into the body of the safe after which the bolts mechanism controlling 25 the door may be easily operated. I propose to prevent this by disposing rearwardly of the lock a frangible receptacle containing an asphyxiating or other disabling gas which will be released by the breaking of 30 said container if the lock is driven forcibly rearward, said gas thereby serving to disable the burglar and to prevent the carrying out of the robbery. It is particularly an object 35 of the present invention to so correlate the container with the lock mechanisms commonly in use that the invention may be employed in conjunction with safes, vaults and the like at present in use and so that it will not be necessary to specially construct a safe 40 or vault in order to incorporate the invention therein.

The figure shown in the accompanying drawing is a horizontal sectional view through a portion of a safe or vaults door 45 illustrating the invention incorporated therein.

In the drawing 5 designates the door of a safe, 6 the usual lock controlling dials and 7 the tumblers of the lock. In safe locks as 50 commonly constructed the bolt mechanism of the door (not shown) cannot be operated until the tumblers 7 have been brought to such position by the manipulation of the dial 6 as to bring the notches 7' in all of 55 said tumblers in alignment. When these

notches are brought into alignment a transverse element 8 of a lever 9 may drop into said notches. It is this movement of the lever 9 that releases the bolt mechanism of the door. It is manifest that if the tumblers 60 be completely removed under the transverse part 8 of the lever 9 the effect will be the same as though all of the notches 7' had been brought into alignment. In other words, the lever 9 may drop. Burglars take 65 advantage of this fact to rob safes by striking off the dial 6 and then punching the spindle 10 straight through into the body of the safe. The lock mechanism is ordinarily disposed in a cavity 11 formed in the door 70 of the safe and access may be had to this cavity by removing a cover 12 which is secured in position by screws 13 and which screws are accessible when the door of the safe is open. There is usually very little 75 space rearwardly of the lock but considerably more space is available within the cavity 11 at the side of the lock. I therefore propose to utilize a container comprising a body portion 14 of considerable capacity and 80 an elongated extension 15, the body portion 14 lying to one side of the body of the lock and the extension 15 projecting into the rear of the lock and in position to be fractured if the spindle 10 is driven rearwardly as 85 above described.

I may increase the space in the rear of the tumblers by providing the cover plate 12 with an offset portion 12a in which the extension 15 is housed. This container is filled 90 with an asphyxiating or other disabling gas such as mustard gas, under such pressure that if the container be ruptured the vicinity of the lock will be filled with a gas of such nature that no human being could remain in 95 the vicinity of the safe or vault. Thus it will be seen that very simple means are provided for effectively guarding against robbery of safes, vaults and the like in the manner above set forth.

It is to be understood that the invention is not limited to the precise construction set forth but that it includes within its purview whatever changes fairly come within either the terms or the spirit of the appended 105 claims.

Having described my invention, what I claim is:

1. The combination with a door and its lock comprising a tumbler mechanism and a 110

spindle, of a frangible receptacle comprising, an elongated portion which projects into the rear of the spindle, and an enlarged body portion which lies to one side of the lock mechanism.

2. The combination with a door having a cavity formed therein and a lock mechanism in said cavity, of a cover plate for said cavity having an offset portion and a container

of frangible material filled with gas and comprising an enlarged body portion and an elongated extension the latter projecting into the offset portion of the cover plate and lying in the rear of the tumbler mechanism.

In testimony whereof I hereunto affix my signature.

LEONARD E. BUMPASS.
